UNITED STATES PATENT OFFICE.

HENRY D. RIDGELY, OF INDIANAPOLIS, INDIANA, ASSIGNOR TO THE
ELI LILLY & COMPANY, OF INDIANAPOLIS, INDIANA, A CORPOR-
ATION OF INDIANA.

DESIGN FOR A BOTTLE.

No. 88,221.

Specification for Design.

Patented Sept. 4, 1906.

Application filed August 12, 1905. Serial No. 274,003. Term of patent 14 years.

To all whom it may concern:

Be it known that I, HENRY D. RIDGELY, a citizen of the United States, residing at Indianapolis, in the county of Marion and State of Indiana, have invented a new, original, and ornamental Design for Bottles, of which the following is a specification.

The accompanying drawings illustrate a bottle, showing my new design.

Figure 1 is a front elevation of a bottle embodying my new design; Fig. 2, a rear elevation, and Fig. 3 a bottom plan view.

As shown in the drawings, my design consists of a bottle having one rounded and two flat sides, the general shape of the bottle in

cross-section being substantially that conventionally known as "diamond-shaped," except that on one side what would in such a shape be two flat sides is made rounding or in the form of a segment of a circle. The neck and mouth of the bottle are of a plain ordinary form.

I claim—

The ornamental design for a bottle substantially as herein shown and described.

HENRY D. RIDGELY. [L. S.]
